UNITED STATES PATENT OFFICE.

HERBERT STUART INDGE, OF WESTBORO, MASSACHUSETTS, ASSIGNOR TO BETHEL-
PLAYER CO., OF WESTBORO, MASSACHUSETTS, A COPARTNERSHIP CONSISTING OF
JOSEPH N. BETHEL AND SIDNEY PLAYER.

LAPPING MACHINE.

Application filed September 5, 1924. Serial No. 736,152.

This invention relates to a machine designed for lapping either flat or cylindrical work and is of the type in which the work is positioned between a fixed and a positively 5 rotated lap.

It is the object of my invention to provide an improved mechanism for giving the work holder certain positive and predetermined movements relatively to the fixed and 10 movable laps.

A further object is to provide means by which the location of movement of the work will be progressively changed relatively to the laps, so that the work will be brought 15 into engagement with all parts of the lapping surfaces.

My invention further relates to arrangements and combinations of parts which will be hereinafter described and more particularly pointed out in the appended claims.

Two forms of the invention are shown in the drawings in which

Fig. 1 is a side elevation of a lapping machine embodying one form of my invention;

25 Fig. 2 is a partial sectional side elevation of that form of my invention shown in Fig. 1;

Fig. 3 is a detail plan view, partially broken away, and taken along the line 3—3

30 in Fig. 2;

Fig. 4 is a view similar to Fig. 3 but showing a work holder for cylindrical work;

Fig. 5 is a diagrammatic view showing the path of movement of the work;

35 Fig. 6 is a partial sectional side elevation showing a second form of my invention;

Fig. 7 is a sectional plan view taken along the line 7—7 in Fig. 6; and

40 Fig. 8 is a sectional view taken on the line 8—8 in Fig. 4.

The general appearance of one form of my improved machine is indicated in Fig. 1, in which I have shown a base or bed 10 having a post or standard 11 on which a

45 head 12 is mounted for both vertical and angular adjustment. A rack bar 13 is vertically adjustable in a bearing 14 at the outer end of an arm 15 carried by the head 12. A fixed or non-rotatable lap 16 is secured to the 50 lower end of the rack bar 13, preferably by a connection which permits the lap 16 to adjust itself to slight variations in height

or level in the surfaces to be lapped. Power may be supplied to the machine in any convenient manner, as by tight and loose pulleys 17 and 18 driven by a belt (not shown) and controlled by a shipper lever 19.

In the form of my invention shown in Figs. 2 to 5, the shaft 20 which is driven by the pulley 17 is provided with a worm 21 (Fig. 2) engaging a worm wheel 22 fixed to a sleeve or cylindrical shell 23 having upper and lower bearings in the bed 10. At its upper end, the sleeve 23 carries a spider or frame 24 to which is bolted the rotatable 65 lap 25. The spider 24 and lap 25 are supported in fixed vertical position by a thrust bearing 26 between the spider 24 and the upper fixed bearing of the sleeve 23.

A work holder 30 is mounted between the 70 fixed lap 16 and the rotatable lap 25 and is provided with recesses adapted to receive the work to be lapped. In Figs. 2 and 3, I have indicated a work holder 30 having circular recesses or openings 31 to receive cylindrical blocks which are to be lapped upon their parallel end surfaces. In Fig. 4, I have indicated a work holder 30^a having openings 32 for cylindrical pieces of work which are to be lapped upon their convex surfaces. 75 These openings 32 are preferably arranged at an angle to a radius drawn therethrough.

I will now describe the special mechanism which I have provided for gyrating the work holders 30 or 30^a and at the same time 80 progressively changing the relation of the work to the fixed and rotatable laps. For this purpose I have provided a head 33 rotatable within and above the spider 24 and fixed to an inner sleeve 35 which is rotatable 85 in bearings within the sleeve 23 and which has a spur gear 36 fixed to the lower end thereof. A corresponding spur gear 37 is fixed to the lower end of the sleeve 23 and is connected to the gear 36 through intermediate gears 38 and 39 mounted on a stud 40 fixed in the base 10.

The ratio of the gearing may be varied as desired but, as shown herein, the gears 37 and 38 are of equal size and the gear 39 is half as large as the gear 36. With this combination of gears, the head 33 will rotate in the same direction as the spider 24 but at only one half of the speed.

A series of three or more studs 41 are fixed in the head 33 and rotatably support a series of pinions 42 which all simultaneously engage a spur gear 43 fixed to a non-rotatable shaft 44 which is secured at its lower end to a portion 45 of the bed 10. As the head 33 is positively rotated at one-half of the speed of the lap 25, the pinions 42 are carried positively around the periphery of the fixed gear 43 and are thus caused to rotate upon their own axes as well as being moved around the axis of the shaft 44 by rotation of the head 33.

Studs or crank pins 50 are mounted in blocks 51 which, are slidably adjustable radially on the enlarged hubs 52 of the pinions 42. A cover-plate 53 encloses the gear 43 and pinions 42 and protects them from dust and dirt.

The crank pins 50 engage openings in the work holder 30 at three or more different points and positively turn the work holder about the axis of the shaft 44 and at a speed one half as great as the speed of the lap 25. At the same time the work holder 30 receives a constant gyrating movement through the revolution of the pinions 42 upon their own axes. If the number of teeth in the fixed gear 43 is not an exact multiple of the number of teeth in the pinions 42, the gyrations will not occur at exactly the same portions of the laps 16 or 25 on successive revolutions of the head 24 but will be advanced or retarded in position, according to the tooth ratio. By changing the ratio between the pinions 42 and the gear 43 the number of gyrations for each revolution of the head 24 and the amount of progressive change in position of gyration for each revolution may be varied as desired.

In Fig. 5, I have indicated the path traced by a point at the center of one of the recesses 31 as it is gyrated and advanced in the machine by the gearing described and shown. It will be noted at 54 (Fig. 5) that the orbit or path of travel is not completed at exactly the same point on the fixed lap at which it began but that the successive paths of travel will be successively advanced relatively to those already formed.

Provision for adjusting the crank pins 50 to vary the throw thereof is clearly indicated in Figs. 3 and 4, the blocks 51 having elongated slots therein through which extend clamping screws which bind the blocks to the hubs 52 in any desired radial position. With this construction, the articles in the work holder 30 may be moved back and forth across any portion of the width of the annular lapping surfaces of the laps 16 and 25.

In Figs. 6 and 7, I have indicated a simplified form of my invention by which substantially the same results may be attained. In this form of my invention the movable lap

60 is bolted to a spider or frame 61 fixed to a vertically extending hollow shaft 62. At the lower end of the shaft 62 any suitable driving connections such as a pulley 63 and belt 63^a may be provided.

A head 64 is mounted for free rotation within and above the spider 61 and is provided with studs 65 on which pinions 66 are rotatably mounted. The pinions 66 support adjustable blocks 67 having studs or crank pins 68 extending into openings in the work holder 69, as in the previous form of my invention. A gear 70 is mounted on the upper end of a fixed shaft 71 and engages the several pinions 66 about its periphery. An annular internal gear 72 is mounted on the spider 61 to rotate therewith, and engages the pinions 66 upon the outer surfaces thereof. A cover 73 is supported on the head 64 and protects the gears 66, 70 and 72.

When the hollow shaft or sleeve 62 and spider 61 are positively rotated by the pulley 63, the ring gear 72 is rotated therewith and causes the pinions 66 to travel around the periphery of the fixed spur gear 70. In this manner the crank pin or studs 68 are rotated about the axes of the pinions and are also progressively advanced relatively to the fixed and movable laps. The resultant path of movement of the work depends upon the gear ratios and may be substantially similar to that already described, and shown diagrammatically in Fig. 5.

When using either form of my invention for cylindrical or conical work, it is necessary that the work holder 30^a be free to revolve upon its own axis at a speed determined by the rolling of the cylinders upon the fixed lap (see Figs. 4 and 8). To permit such free rotation, I insert a carrier plate 75 between the driving studs or crank pins 50^a and the work holder 30^a. This carrier plate 75 has openings 76 to receive the studs 50^a and has a central stud 77 on which the work holder 30^a is loosely fitted. The studs 50^a are preferably somewhat shorter than the studs 50 in the regular form of the machine and do not project above the top surface of the fixed lap 25. When thus mounted, the work holder 30^a receives an eccentric movement from the studs 50^a but is also free to rotate about its center on the stud 77.

Having thus described two forms of my invention, it will be seen that I have provided a lapping machine in which the work holder has a general movement in a positive and predetermined relation to the movement of the rotatable lap and in which the work holder is also gyrated or moved transversely in such a way that the work is moved back and forth across the face of the laps to engage the entire working surface thereof. In this way the full value of the entire lapping surface is utilized.

Having thus described two forms of my invention, I do not wish to be limited to the details herein disclosed otherwise than as set forth in the claims, but what I claim is:—

- 5 1. A lapping machine having a fixed lap, a positively rotated lap, a work holder mounted between said laps, and means to rotate said work holder and to give said holder a plurality of positive and definite gyrating movements during each rotation of said holder relative to said fixed lap.
- 10 2. A lapping machine having a fixed lap, a positively rotated lap, a rotatable work holder mounted between said laps, devices
- 15 rotatable about a plurality of parallel axes effective to give said work holder a plurality of positive and definite gyrating movements during each rotation of said work holder, and positive means to progressively advance
- 20 20 said devices relatively to the fixed lap, thereby by rotating said holder.
- 25 3. A lapping machine having a fixed lap, a rotatable lap, a work holder mounted between said laps, means to give said work holder definite gyrating movements about a plurality of parallel axes, means to progressively advance said axes relatively to the fixed lap, and means to permit adjustment of the extent of said gyrating movements.
- 30 4. A lapping machine having a fixed lap, a positively rotated lap, a work holder mounted between said laps, a rotatable head, means to drive said head and rotatable lap in a definite speed relation, a gear mounted
- 35 in fixed position concentric with said head, a plurality of pinions mounted on said head on parallel axes eccentric to the axis of said head, and crank pins on said pinions effective to gyrate positively said work holder,
- 40 said pinions being also continuously advanced by the rotation of said head to positively rotate said work holder.
- 45 5. A lapping machine having a fixed lap, a rotatable lap, a work holder mounted between said laps, a rotatable head, means to drive said head and rotatable lap in a definite speed relation, a gear fixed in position concentric with said head, a plurality of pinions mounted on parallel axes eccentric to
- 50 the axis of said head, crankpins on said pinions effective to gyrate and rotate said

work holder, and means to permit adjustment of the throw of said crankpins.

6. A lapping machine having a fixed lap, a positively rotated lap, a work holder 55 mounted between said laps, a freely rotatable head, pinions mounted on said head at points spaced from the axis thereof, crankpins on said pinions engaging said work holder to gyrate and rotate the same, a fixed gear 60 simultaneously engaging all of said pinions at one point thereof, and a driven gear engaging said pinions at other points thereof to positively rotate said pinions and also progressively advance the same relative to 65 the fixed gear.

7. A lapping machine having a fixed lap, a positively rotated lap, a work holder mounted between said laps, a freely rotatable head, pinions mounted on said head at 70 points spaced from the axis thereof, crankpins on said pinions engaging said work holder to gyrate and rotate the same, a spur gear engaging each of said pinions, an internal gear also engaging each of said pinions, and means to drive one of said gears. 75

8. A lapping machine having a fixed lap, a positively rotated lap, a work holder mounted between said laps, a freely rotatable head, pinions mounted on said head at 80 points spaced from the axis thereof, crankpins on said pinions engaging said work holder to gyrate and rotate the same, a fixed spur gear engaging each of said pinions, an internal ring gear also engaging each of said 85 pinions, and means to positively rotate said internal gear.

9. A lapping machine having a fixed lap, a positively rotated lap, a work holder mounted between said laps, a freely rotatable 90 head, pinions mounted on said head at points spaced from the axis thereof, crankpins on said pinions engaging said work holder to gyrate and rotate the same, a fixed spur gear engaging each of said pinions, an internal ring gear also engaging each of said 95 pinions, and means to simultaneously rotate said internal gear and said rotatable lap.

In testimony whereof I have hereunto affixed my signature.

HERBERT S. INDGE.
